Fig. 9.

FIG. 1 is a bottom plan view of luminaire lens showing my new design;

FIG. 2 is an enlarged fragmentary bottom plan view thereof;

FIG. 3 is a cross-sectional view thereof taken along line 3-3 of FIG. 2;

FIG. 4 is an enlarged fragmentary top plan view thereof;

FIG. 5 is a cross-sectional view thereof taken on line 5-5 of FIG. 4;

FIG. 6 is an enlarged fragmentary bottom perspective view thereof;

FIG. 7 is a bottom plan view of a second embodiment of my design;

FIG. 8 is an enlarged fragmentary bottom plan view thereof;

FIG. 9 is a cross-sectional view thereof taken along line 9-9 of FIG. 8;

FIG. 10 is an enlarged fragmentary top plan view thereof;

FIG. 11 is a cross-sectional view thereof taken along line 11-11' of FIG. 10;

FIG. 12 is an enlarged bottom perspective view thereof. The prismatic structure is partially shown on the lens in FIGS. 1 and 7 for convenience of illustration, it being understood that the prismatic structure is continuous over the surface of the lens. The lens is understood to have indeterminate length and width.

I claim:

The ornamental design for a luminaire lens, substantially as shown and described.
